CLAIM

The ornamental design for a vehicle fog light bezel, as shown and described.

DESCRIPTION

FIG. 1 is a perspective view of a vehicle fog light bezel that resides on a rightside of the vehicle (the leftside vehicle fog light bezel being a mirror image of this rightside vehicle fog light bezel);

FIG. 2 is a front view thereof;

FIG. 3 is a rightside view thereof; and,

FIG. 4 is a top view thereof.

The broken lines in the drawings illustrate portions of the vehicle fog light bezel that form no part of the claimed design.
